UNITED STATES PATENT OFFICE.

DAVID F. CRAWFORD, OF PITTSBURGH, PENNSYLVANIA.

COMPOUND RAIL.

1,098,614.

Specification of Letters Patent. Patented June 2, 1914.

Application filed December 30, 1912. Serial No. 739,218.

To all whom it may concern:

Be it known that I, DAVID F. CRAWFORD, a citizen of the United States, residing at Pittsburgh, in the county of Allegheny and State of Pennsylvania, have invented certain new and useful Improvements in Compound Rails, of which the following is a specification.

The invention relates to compound or built-up rails wherein the composition of the upper and lower portions of the rails may be varied to suit conditions, the lower portion being preferably made of tough low carbon steel, and the upper portion of harder steel having a higher carbon content and increased wearing qualities. The invention has for its primary objects the provision of a built-up rail in which the parts of the rail are clamped together with a great degree of security; the provision of a rail in which the parts may be rapidly assembled and disassembled to permit of quick replacement of worn parts; and the provision of a compound rail section which can be used with the ordinary unitary rail section and in which adjoining sections of track may be properly secured together in alinement. One embodiment of the invention is shown in the accompanying drawings wherein—

Figure 1 is a cross section through the rail, on the line I—I in Fig. 4, the clamping means being shown in end elevation; Fig. 2 is a section on the line II—II of Fig. 4, and shows the splice bars in end elevation; Fig.

3 is a section through the rail at a point where insulating means are employed for insulating the rail from the ground; Fig. 4 is a side elevation of the rail structure on a reduced scale; Fig. 5 is a section on the lines V—V and V'—V' of Fig. 6, the left hand side of Fig. 5 being taken on the line V—V, and the right hand side being a section taken on the line V'—V'; and Fig. 6 is a side elevation of the connecting piece employed where a compound rail of the present application is joined to a rail of ordinary cross section.

Referring to Figs. 1 and 4, 1 is the head of the rail which is made of relatively hard or high carbon steel in order to resist wear, and 2 is an I section of very tough low carbon steel, upon which there is substantially no wear, and which is therefore of a texture adapted to resist strains and entirely lacking the brittleness of extremely hard high carbon steel. The members 1 and 2 are of

course commercial rolled sections, and may be made of any desired proportions, the weight of the two sections per unit length being somewhat greater than that of the ordinary rail designed for the same service.

The two sections 1 and 2 are held together by means of clamping members 3 and 4 placed along the sections at appropriate intervals, depending upon conditions, as indicated in Fig. 4. These clamping members are held securely in place by means of the bolts 5, any suitable type of nut lock being employed with the nuts of the bolts. The clamp 4 on one side of the sections 1 and 2 is provided with a hook-shaped portion 6 at its upper edge, and between edge 6 and the flange of the section 1 a key 7 is interposed, such key 7 being angular in cross section as indicated in Fig. 1, and being of substantially the same length as the clamping member 4.

The purpose of the key or wedge member 7 is to permit of the more ready removal of the upper section 1 for replacement or repair, as by knocking out this key 7 the section 1 can be removed without removing the nuts on the bolts 5. The section 2 of the rail is substantially permanent, there being no wear upon this section, so that all replacements due to wear or breakage are limited to the upper section 1, and the cost of maintenance is obviously smaller than in the case where the entire section has to be renewed to renew the track.

Figure 2 illustrates the construction employed where two rail sections are secured together at their ends. The clamping members 8 and 9 employed to fasten the joints are quite similar to the members 3 and 4 shown in Fig. 1, but are longer as indicated in Fig. 4, and in order to give additional strength, have their flanges extended down around the flanges of the section 2. The central portions of the members 8 and 9 are also spaced away from the web of the section instead of engaging the web of the section 2, the clamping members in this respect following the usual practice employed in the construction of splice bars. The members 8 and 9 are secured in place by means of the bolts 11.

Fig. 3 illustrates the construction employed where it is desired to insulate the rail. In this construction the flanges of the sections 1 and 2 are held together by means of the U-shaped clips 12, and these mem-

bers are secured by means of the screws shown in the blocks of wood 14-14. Metal plates 15 and 16 engage both sides of the wooden blocks 14-14 and are clamped in position by means of the bolts 16. The plate 16 has a flange 18 extending beneath the section 2 and an insulating strip 19 is provided upon the inside surface of the plate 16 and flange 18. The bolt is also insulated by means of the collars 20 and the washers 21.

Figs. 5 and 6 illustrate the construction employed where the compound rail is secured to the end of the ordinary rail 22. In order to provide for this connection a metal block 23 is employed having at the end the part 24 which extends beneath the end of the rail 22 as indicated in Fig. 5. The hooked portions 25 extend over the edge of the rail. It will be seen that the rail 22 may be positioned in the block 24 by endwise movement. The wings 26 of the block 23 are constructed as indicated in Fig. 5, and are so formed as to embrace the outside of the sections 1 and 2. The wings 26 are provided with the holes 27 adapted to receive bolts for clamping the wings tightly against the web of the sections 1 and 2. It will be noted that the wings 26 are provided with flanges 28 by means of which the block may be spiked in place to the ties.

Having thus described my invention and illustrated its use, what I claim as new and

desire to secure by Letters Patent, is the following.

1. In combination in a compound rail, a lower I section, an upper tread section resting on the top of the lower section and provided with a pair of flanges, releasable means for clamping one of the said pair of flanges to the lower section, and clamping means for the other of said pair of flanges comprising a clamp bolted to the lower section and having an overhanging portion above such other flange, and a key wedged between the said overhanging portion and the said other flange of the tread section. 45

2. In combination in a compound rail, a lower I section, an upper tread section resting on the top of the lower section and provided with a pair of flanges, a pair of clamps on opposite sides of the rail with overhanging edges for securing the said flanges of the tread section, a key interposed between one of the said overhanging flanges and the opposing flange of the tread section, and a bolt for securing the clamps against the sides of the lower section. 55

In testimony whereof I have hereunto signed my name in the presence of the two 60 subscribed witnesses.

DAVID F. CRAWFORD.
